UNITED STATES PATENT OFFICE

2,515,070

SNOWSHOE OR SWAMPSHOE

David F. Anderson, Camden, Maine, assignor to
Fiberlast of Canada (Ltd.), St. Jerome, Quebec,
Canada, a corporation of Canada.

Application April 30, 1949; Serial No. 90,615

7 Claims. (Cl. 36—4.5)

1

Introduction

This invention relates to a snowshoe or swampshoe.

The conventional snowshoe is a racket-like structure, including a wooden frame and rawhide or leather stringing. This structure has certain disadvantages. For example, it is heavy. The stringing has to be treated periodically to prevent it from ageing. Moreover, the article does not lend itself to mass production.

In the prior art, attempts have been made to partially overcome these disadvantages by providing all metal snowshoes, or snowshoes with webbings of metal mesh or wire. While these do provide some of the advantages desired, in general, this form of snowshoe is heavy and moreover, does not present a flexible bearing surface to the feet of the wearer.

The applicant recognizes these problems and aims to provide a practical solution for them by developing a light, sturdy, snowshoe structure that combines the desired flexible qualities of the conventional snowshoe with the strength, and weather resistant qualities of the metallic type of snowshoe. Further, the present snowshoe structure lends itself to mass production methods, thus facilitating its manufacture in large quantities.

Applicant's development

In accordance with the foregoing, the present invention consists of a snowshoe having a metal frame including an outer frame having the general outline of the snowshoe, cross beams adapted to brace the outer frame transversely, and an inside frame that rests on the cross beams to form a reinforced foot supporting portion. Moulded on and about the metal frame is a covering of light moisture impervious mouldable material to complete the outline of the shoe body, and to provide the webbing of the shoe.

More specifically, the preferred construction of the snowshoe according to the invention comprises of a metal outer frame of light metal rod or tubing that extends completely about the outer periphery of the shoe. This metal outer frame is formed in the general outline of a conventional snowshoe, and is bridged across by a front beam member and a rear beam member that extend up from the outer frame and across the shoe in spaced apart relationship, so as to form supports and load transmitting members for the cover or skin of the shoe adjacent the front and rear of the shoe structure. The preferred covering of the shoe comprises a fibrous

2

material that is bonded together with a heat-reactive resin varnish, for example, "Fiberglas" bonded with "Laminac" resin. This covering is moulded on a suitable form with the metal frame in position so that the covering and frame members are bonded together into one homogeneous structure.

In the preferred form, a metal rod inner frame is positioned centrally beneath the shoe covering and secured between the cross beam members so as to form a reinforced foot supporting portion and the covering of the shoe is moulded on the frame so as to have a dished contour with downwardly extending flanges about the outer periphery of the shoe. These flanges together with the cross beams of the frame which extend beyond the lower surface of the covering provide traction members, and slots or holes are provided about the outer periphery of the shoe for the attaching of rawhide thongs for additional traction if the shoe is to be used on ice or glaze covered snow.

The frame and covering of the shoe adjacent the front end is formed so as to curve upwards similarly to the conventional snowshoe, and due to the multiple curvature employed provides great resistance to bending between the heel and toe.

Detailed description

Having thus generally described the nature of the invention, reference will be made to the accompanying drawings in which:

Figure 1 is a plan view of a preferred form of snowshoe according to the present invention.

Figure 2 is a side elevation of the snowshoe shown in Figure 1.

Figure 3 is a section on the line 3—3 of Figure 1.

Figure 4 is a section on the line 4—4 of Figure 1.

With particular reference to the drawings, a snowshoe constructed according to the invention includes a metal rod or tubular outer frame 11 that is formed in the general outline of a conventional snowshoe and extends completely about the outer periphery of the shoe. This outer frame 11 is bridged across by a front beam (made up of a frame member 12 and a wooden filler piece 13) and a rear beam 16, both bridges extending upwards from and spanning the outer frame 11 across the skins 19, in spaced apart relationship, so as to form load transmitting and supporting members adjacent to the front and rear of the shoe.

The frame member 12 includes downwardly extending end portions 15 that are connected to the frame 11, and a wooden filler piece 18 is positioned relative to the frame member 12 so that it is supported by this member beneath the skin 19.

The rear beam comprises of a metal rod 16 that includes downwardly extending portions 17 that are connected to the frame 11. It is also contemplated that the composite front beam formed by the frame 12 and the filler 18 could equally well be provided by a sheet metal structure or tubing formed in the shape of a hollow bridge, the main requisite being that the front beam be sufficiently strong to support the main weight of the wearer and that it is arranged so as to transmit this weight to the outer periphery of the shoe.

An inner frame 20, preferably made of wire rod is secured between the front beam and the rear beam and is formed so that it connects these two beams together and provides a reinforcing for the foot supporting area of the covering 19.

The covering 19 comprises fibrous glass or other fibrous material, bonded together with a heat reactive resin, for example "Fiberglas" bonded with "Laminac" resin. The covering 19 is moulded on a suitable form with the metal frame members in position so that the covering 19 and the outer frame 11, together with the front and rear beams and the reinforcing frame 20 are bonded together to form the complete shoe.

The frame 11, and the covering 19 adjacent the front end of the shoe are formed so as to curve upwards similarly to a conventional snowshoe and the covering 19 is moulded on to the frame so as to give the covering 19 a dished contour with downwardly extending flanges surrounding the outer periphery of the shoe.

A suitable foothole 21 is provided in the covering 19 adjacent the front beam, and the supporting frame 20 preferably extends beyond the front beam so as to provide a reinforced edge to this opening. Slots 22 are also provided in the covering 19 adjacent the front beam so that the usual lashings can be secured to the shoe for attaching purposes.

The front and rear cross beams extend below the surface of the covering 19 so as to provide traction members and in conjunction with the downwardly extending flanges formed completely about the shoe, give the shoe a "grip" equal to that afforded by the open webbings of the conventional shoe.

To supply further traction, as may be needed when hard snow or ice is encountered, spaced apart holes 23 are provided along the outer edges of the shoe at both sides. These holes 23 extend along the major part of the bearing surface of the shoe, and thongs 24 are wound about the frame 11 through these holes so as to provide additional traction.

The upper surface of the covering 19 of the shoe that is adapted to come beneath the wearer's foot can be roughened if desired by the application of carborundum, sand, or other non-skid material when the covering is being molded in place.

Operation

The snowshoe is used as a conventional shoe. The area surrounded by the outer frame 11 constitutes the surface of the snowshoe which rests on the snow, muskeg, or swamp. The area sur-

rounded by the inner frame 20 constitutes a foot-supporting portion. This portion is somewhat flexible to prevent jarring the foot. The front portion above the frame piece or beam 18 forms a substantially non-resilient bearing for the front portion of the foot. The skin can be made very strong when using "Fiberglas" base bonded with a "Laminac" resin. The particular shape of the shoe tends to accentuate its strength and a shoe made to this design when supported only at the toe and heel of the shoe, will bear the weight of a man of over 200 pounds weight.

I claim:

1. A snowshoe comprising a substantially rigid outer frame, a covering of resin bonded fibrous glass material moulded on said frame so as to fill the enclosure of said frame and reinforcing cross members connected to said frame and bonded to said covering material.

2. A snowshoe comprising an outer frame of light metal, a covering of fibrous glass material bonded with a heat reactive resin moulded on said metal frame so as to fill the enclosure of said frame, and reinforcing cross members connected to said frame and bonded into attachment with said covering material.

3. A snowshoe comprising an outer frame of light metal, reinforcing cross members connected to and extending upwardly from said outer frame to span said outer frame adjacent the front and rear, a covering of bonded fibrous material moulded on said outer frame and cross members, said covering being shaped to form with the frame a snowshoe structure having a dished-up contour with downwardly extending flanges extending completely about the outer periphery of the shoe, said flanges terminating in a bulbous edge formed by said metal outer frame and openings in said covering adjacent said front cross member to provide for entrance of the toe portion of the foot, and to accommodate lashings to attach the shoe.

4. A snowshoe as claimed in claim 3, wherein said covering is made of fibrous glass material bonded with a heat reactive resin.

5. A snowshoe comprising an outer frame of light metal, reinforcing cross members connected to and extending upwardly from said outer frame to span said outer frame adjacent the front and rear, said front cross member being constituted by a metal frame having downwardly extending end portions that are connected to said outer frame and a wooden filler member resting on said metal frame, said rear cross member being constituted by a metal frame having downwardly extending end portions connected to said outer frame, a covering of fibrous glass material bonded with a heat reactive resin moulded on said outer frame and cross members, a substantially U-shaped metal frame supported between said front and rear members beneath said covering to constitute a reinforced foot supporting portion, said covering being moulded to form with the frame a homogeneous structure having a dished-up contour including downwardly extending flanges extending completely about the outer periphery of the shoe, said flanges terminating in a bulbous edge formed by said metal outer frame, and cut out portions in said covering constituting openings adjacent said front cross member to provide for entrance of the toe portion of the foot, and to accommodate lashings adapted for shoe attachment.

6. A snowshoe as claimed in claim 5, wherein the cross members and U-shaped reinforcing frame project downwardly beneath the covering to constitute traction members.

7. A snowshoe as claimed in claim 5, including openings along the peripheral edge of the covering adjacent to said metal outer frame and rawhide lashings threaded through said openings and about the frame to provide traction members.
